UNITED STATES PATENT OFFICE.

HIRAM PERCY MAXIM, OF HARTFORD, CONNECTICUT, ASSIGNOR TO THE MAXIM
SILENCER COMPANY, OF HARTFORD, CONNECTICUT, A CORPORATION OF CON-
NECTICUT.

SILENCER.

1,330,486.

Specification of Letters Patent. Patented Feb. 10, 1920.

Application filed December 18, 1917. Serial No. 207,780.

To all whom it may concern:

Be it known that I, HIRAM PERCY MAXIM, a citizen of the United States, residing at Hartford, in the county of Hartford and State of Connecticut, have invented certain new and useful Improvements in Silencers, of which the following is a specification.

This invention relates to silencers. A silencer involving the invention is obviously capable of general use, although it is of particular utility when used in conjunction with gas engines, such for illustration as are employed for the operation of automobiles. Among the several objects I have in view is the provision of an article of the character set forth, which is simple in construction, which can be inexpensively made, and the parts of which can be readily and quickly assembled, and which is highly effective for eliminating as far as practicable, the objectionable noises created by the exhaust.

In the drawings accompanying and forming part of the present specification I have shown in detail one convenient form of embodiment of the invention which will be set forth fully in the following description. I do not necessarily restrict myself to this disclosure; I may depart therefrom in many respects within the scope of the invention defined by the claims following said description.

Referring to said drawings:

Figure 1 is a longitudinal section of a silencer embodying the invention. Fig. 2 is a cross section on the line 2—2 of Fig. 1, looking in the direction of the arrow, and

Fig. 3 is a detail view in perspective of a disk.

Like characters refer to like parts throughout the several views.

The silencer comprises in its organization a suitable body, the practically cylindrical shell or casing 2 answering satisfactorily in this respect. This shell as shown has the ends 3 and 4 which in the present case are virtually of disk form and are set within the terminal portions of the body or shell 2. Said ends have peripheral outturned flanges 5 united by spot welding or otherwise to the body to thus produce close joints.

As I have already stated the appliance is especially intended for use in silencing the exhaust of a hydrocarbon engine. The exhaust may be led into the silencer in

various ways. For this purpose the head 3 is shown as having an inlet 6 in the form of a short length of tubing adapted for slip or other suitable connection with the exhaust-pipe of an engine of the kind set forth. This tube as illustrated projects through a central opening 7 in the disk 3 and is rolled over the wall of the opening 7 as at 8 on the inner face of the end 3. The tube 6 also has an annular circumferential enlargement or bulge 6' fitted against the outer face of said end 3. The outlet of the silencer in like fashion may be of any desirable nature; that shown is designated by 9, being in the form of a tube which is longitudinally tapered from its entering toward its discharge end. The butt portion of said discharge tube or nozzle 9 is fitted in a practically central opening 10 in the head 4 and is turned over the wall of said opening 10 as denoted by 11.

The silencer member which I have shown, is denoted in a general way by 12 and it is preferably spaced or separated from the inlet or receiving end of the silencer as shown by 13. The space 13 is unobstructed to permit the free expansion of the exhaust gases before they strike the silencer member or body 12. The silencer member or body 12 as represented comprises several units 14 which are in the form of metal disks, it being understood also that the several parts already described are of metal or other proper material. These units or disks 14 are radially slit as at 15 from their peripheries to and across their centers, the stock at opposite sides of the respective slits being oppositely deflected as at 16 and 17 to produce in effect wings at opposite sides of the opening 21. The disks are set into the shell 2 at the discharge end thereof and their perimeters preferably touch and practically substantially engage the inner surface of the shell 2. It will be noticed that the oppositely deflected wings 16 and 17 are in overlapped relation virtually radially of the respective disks. This is shown in both Figs. 2 and 3, and more especially in the latter view, wherein the wing overlaps the wing 17. In view of this circumstance I can positively insure the lateral flow of the gases, so that in passing through the silencer, they will definitely follow a spiral trend. It will be also observed that the rear wing of each plate or disk is in overlapped rela-

tion with the forwardly extending wing of the plate back of it, that is in the line of flow of the gases. This is a further aid to the motive in view.

5 Said disks 14 are united together in any desirable manner, as by the bolts 18, there being as shown four of such bolts which are equidistantly spaced and which project through perforations in the head 4 and also 10 through perforations in the several disks, the threaded ends of the bolts or tie members 18 receiving nuts as 19 engaging against the initial disk 14. In addition to this the bolts also carry the tubes 20 interposed between 15 the several units or disks 14 and also between the final disk and the end 4, this providing a convenient way of spacing the parts properly and for maintaining the same in proper rigid relation with each other and 20 with the casing.

The exhaust gases from the engine entering the silencer by way of the inlet tube 6 initially pass into the free or open space 13, wherein they expand. They then strike 25 the primary disk 14 and then the second disk and so on throughout the series, leaving the body 2 through the tapered or downturned discharge tube. The gases pass through the silencer in a spiral or serpentine path. On striking the first disk they escape through the first opening or orifice 21, by which they are diverted laterally and after passing through this first opening or orifice strike the second disk where they are 30 further whirled, passing through the opening of the second disk and taking a lateral direction opposite the first, strike the third disk and so on throughout the series. As the gases pass through the respective orifices or openings 21 which jointly or collectively present a helical passage, those at and near the axes of the respective disks travel obviously a less distance than those farther away from the axes, the result being that 45 the gases leave the discharge tube 9 gradually and in an attenuated stream.

The part 12 composed of the several plates or disks, and as I have also considered them units, presents in itself a unit, and this observation applies when said part 12 is associated with the end or closure member 4. This silencer element 12 made up of the connected plates or disks can be especially when operatively associated with the end or 50 its equivalent 4, handled as an article of manufacture and therefore presents the attributes of a unit.

From the foregoing description taken in connection with the annexed drawings, it 55 will be evident that a silencer embodying the invention, involves a case having an inlet and an outlet. In this case is situated silencing means between the inlet and the outlet, which comprises a number of units, plates or disks in connection with mecha-

nism for associating said plates to form an irregular passage between the inlet and the outlet. The first of these units or plates is spaced from the inlet a greater distance than that between the last of the units and the outlet to form an expansion chamber in which the gases are received before entering said irregular passage which is of such nature desirably to impart a rotary motion to the gases. It is of course not always necessary that these units or plates should touch the inner surface of the case. The units or plates are desirably connected only with the outer end head of the case. While the silencer is of course capable of general use 70 it is especially adapted for connection with engines which use heavy oil. The exhaust of the heavy oil is first discharged into the chamber or space at the front end of the case. The heavy particles in the exhaust, 75 are precipitated in this chamber and are prevented as far as practicable from entering the spiral or helical silencing passage so that the latter is free to exercise its silencing function. Should these particles enter the 80 passage in question they so clog and choke it as to reduce the efficiency of the engine by causing back pressure. These particles are liquid, heavy and sooty. It will be also observed that the spiral silencing passage 85 presented jointly by the several units, plates or disks, is of smaller extent cross-sectionally than its length by reason of which the maximum efficiency in silencing is obtained. The units or plates are connected as shown 90 by bolts which are associated, by direct connection, with the outer or outlet head or end of the casing.

What I claim is:

1. A silencer comprising a body having 105 an inlet and an outlet; and a plurality of spaced disks in the body between the inlet and the outlet, touching the inner surface of the body, and each disk being slit from the periphery toward the center, the portions 110 adjacent the slit being laterally oppositely spread to produce wings and being imperforate where slit and the central portion of each disk across which the slit extends being imperforate except where slit. 115

2. A silencer comprising a body having an inlet and an outlet, and a plurality of spaced disks in the body between the inlet and the outlet, touching the inner surface of the body and each disk being slit from 120 the periphery toward and across the center, the portions adjacent the slit being laterally oppositely spread to produce wings and being imperforate except where slit.

3. An article of manufacture for use in 125 silencers comprising a plurality of disks spaced from each other and rigidly connected, each disk being slit from the periphery toward the center, the portions adjacent the slit being spread oppositely to 130

produce wings and being imperforate except where slit.

4. An article of manufacture for use in silencers comprising a plurality of rigidly connected disks spaced from each other, each disk being slit radially from the periphery toward and across the center, the portions adjacent the slit being spread oppositely to produce wings and being imperforate except where slit.

5. A silencer comprising a body having an inlet, and an outlet, and a plurality of spaced plates in the body between the inlet and the outlet, touching the inner surface of the body, each plate being slit from its periphery toward the center, the portions adjacent the slit being laterally oppositely spread to produce wings, the plates being imperforate except where slit, the wings of the respective plates being in overlapped relation.

6. A silencer comprising a body having an inlet and an outlet, and a plurality of spaced plates in the body between the inlet and the outlet touching the inner surface of the body, each plate being slit from its periphery toward and across its center, the portions adjacent the slit being laterally oppositely spread to produce wings, the wings of the respective plates being in overlapped contact, the plates being imperforate except where slit.

7. A silencer comprising a substantially cylindrical body, one end wall of which has an inlet tube and the other end wall of which has a downwardly extending outlet tube, and a plurality of spaced connected plates in the body between the inlet tube and the outlet tube, touching the inner surface of the body, each plate being slit from its periphery toward and across its center, the portions adjacent the slit being laterally oppositely spread to produce wings, the wings of the respective plates being in overlapped contact, the plates being imperforate except where slit.

8. An article of manufacture for use in silencers, comprising a plurality of disks spaced apart from each other and rigidly connected, each disk being slit from the periphery toward the center, the portions adjacent the slit being spread oppositely to produce wings to form a spiral passage at least the first of the disks being otherwise imperforate.

9. A silencer comprising a body having an inlet and an outlet, a plurality of spaced disks in the body between the inlet and the outlet, each disk being slit from its periphery toward the center, the portions adjacent the slit being laterally oppositely spread to produce wings whereby the disks form a spiral passage, at least the first of the disks being otherwise imperforate.

10. An article of manufacture for use in

silencers comprising a plurality of disks spaced from each other and rigidly connected, each disk being slit from the periphery toward the center, the portions adjacent the slit being spread oppositely to produce wings which are united with each other to form a spiral passage at least the first of the disks being otherwise imperforate.

11. An article of manufacture for use in silencers comprising a plurality of rigidly connected plates spaced from each other each plate being slit radially from the periphery toward the center thereof, and spread oppositely to produce wings rigidly connected respectively with each other the central portions of the plates except where slit being imperforate.

12. A silencer comprising a plurality of units in the case in the form of plates, the plates having means associated therewith to form a spiral duct to convey exhaust gases, and the duct being of less cross sectional extent than its length at least the first unit except for said duct being imperforate.

13. A silencer comprising a case, a plurality of units in the case in the form of plates, the plates having means associated therewith to form a spiral duct to convey exhaust gases, the duct being of less cross sectional extent than its length, and the duct being of angular form in cross section, the first plate except for said duct being imperforate.

14. A silencer involving a case having an inlet and an outlet, silencing means in the case, between the inlet and the outlet, comprising a number of units and bolts for connecting said units to form a spiral passage between the inlet and the outlet the bolts being connected only with the outlet end of the case, the first of the units being spaced from the inlet end a distance such as to form an expansion chamber in which the gases are received before entering said passage.

15. A silencer comprising a case having an inlet and an outlet, silencing means in the case, comprising a plurality of distinct members, and means for rigidly connecting the members to each other and to the case, the silencing means having a spiral duct to convey exhaust gases, the duct being of less cross sectional extent than its length, that part of the silencing means next the inlet being imperforate except for said duct.

16. An article of manufacture for use in silencers, comprising a plurality of rigidly connected plates spaced from each other each plate being slit radially from the periphery toward the center thereof, the portions adjacent the slit being spread oppositely to produce wings the central portions of the plates except where slit being imperforate.

17. A silencer comprising a case having an inlet and an outlet respectively in the ends thereof, silencing means in the case,

having a spiral passage for conducting the gases from the inlet to the outlet, and bolts connecting the silencing means solely with the outlet end of the case.

- 5 18. A silencer comprising a case having an inlet and an outlet respectively in the ends thereof, silencing means in the case having a spiral passage for conducting the gases from the inlet to the outlet, and means 10 for positively connecting the silencing means solely with the outlet end of the case, at a plurality of places.

19. A silencer comprising a case having an inlet and an outlet respectively in the 15 ends thereof, silencing means in the case having a spiral passage for conducting the

gases from the inlet to the outlet, the length of the passage being greater than its width, and means for connecting the silencing means solely and positively with the outlet 20 end of the case, at a plurality of places, the space between the inlet end of the case and the silencing means being greater than that between opposite ends of the silencing means and the outlet end of the case. 25

In testimony whereof I affix my signature in the presence of two witnesses.

HIRAM PERCY MAXIM.
